[57] CLAIM

The ornamental design for an enclosure for data processing system, as shown and described.

DESCRIPTION

FIG. 1 is a front perspective view of an enclosure for data processing system showing our new design; FIG. 2 is a top plan view thereof on a reduced scale; and FIG. 3 is a side elevational view thereof on a reduced scale, the opposite side being a mirror image.

FIG. 1

FIG. 2

FIG. 3
